UNITED STATES PATENT OFFICE.

ASA O. DENIO, OF WILMINGTON, DELAWARE.

IMPROVEMENT IN LOCOMOTIVE ASH-PAN CLEANERS.

Specification forming part of Letters Patent No. **141,769**, dated August 12, 1873; application filed April 26, 1873.

To all whom it may concern:

Be it known that I, A. O. DENIO, of Wilmington, New Castle county, Delaware, have invented a Locomotive Ash-Pan Cleaner, of which the following is a specification:

The object of my invention is to readily discharge from a locomotive ash-pan the accumulated ashes which interfere with the draft, and at the same time extinguish and render harmless the ignited portions of such ashes.

These objects I attain by so combining with a locomotive ash-pan, *c*, a nozzle, *D*, communicating with the water-space of the boiler, as shown in Figure 1 of the accompanying drawing, that, when communication between the boiler and nozzle is opened, a forcible jet of water under the pressure will extinguish the ignited ashes, and at the same time expel them from the pan.

The nozzle *D*, which I prefer to make of the fish-tail shape shown in the detached view, Fig. 3, so as to insure a widely-diffused jet, is secured to the lower end of a pipe, *B*, passing down the front of the boiler, and connected at its upper end to a cock, *A*, communicating with the water-space of the boiler and having a handle within reach of the attendant engineer.

In the present instance the pipe *B* is so connected to the cock and to the boiler that it

can be turned laterally by means of a handle, *E*, which enables the engineer to direct the jet to all parts of the ash-pan. It is important that the ignited portions of the ashes should be extinguished before, or as they are being discharged from the ash-pan onto the track. Otherwise the particles of ignited fuel might be dispersed by the wind and endanger neighboring buildings; hence water only is discharged from the nozzle.

I am aware that a steam-jet has been employed for removing obstructions from boiler-tubes of locomotives; and I, therefore, do not claim, broadly, the combination, with a locomotive, of an injecting nozzle and pipe communicating with the boiler. It will be apparent, however, that owing to the arrangement of the ash-pan the devices hitherto employed for cleaning flues could not be used for removing the ashes from below the grate-bars.

I claim—

The combination described, with a locomotive ash-pan, of a nozzle directed to the pan, attached to the boiler and to a cock communicating with the water-space of the boiler, all substantially as and for the purpose set forth.

ASA OBER DENIO.
